CONTROL SHUTTER FOR ENGINE
RADIATORS

Udo K. Johannsen, Cortland, N. Y., assignors to
The Brewer-Titchener Corporation, Cortland,
N. Y., a corporation of New York

Application November 3, 1931. Serial No. 572,753

10 Claims. (Cl. 189—62)

This invention relates to improvements in the art of operable cold-weather shields or shutter regulator fronts adapted to control air-flow to a radiator as applied to water-cooled vehicle motors, and is more particularly directed to a combined shutter and grille in which their common supporting frame may readily be attached to existing radiator shells.

The present improvements aim to enhance the appearance of attachable shutter installations by the use of a screen or grille-work mounted as a unit within the shutter frame and serving to mask my shutter devices therebehind. To this end, the radiator shell that houses the core and tank, may be given a U-shaped contour as formed up from a channel-profile strip. The front face of such radiator shell is herein neatly trimmed by means of a similarly formed framework carrying spaced inset panels with vertical shutter slats mounted therebetween; said grille is cooperatively disposed ahead of such shutter assembly in the same fenestrated frame that mounts said slats.

The object of my invention is to provide for a simple and smartly designed automobile appurtenance of the character indicated, including suitable arrangements for building up a false V-shaped shutter front serving to effectively enhance the appearance of the motor car or truck to which it may be applied.

In order to accomplish the cited new and useful results, said improvements further consist in novel structural features and combinations thereof, also in an attractive, compact disposition of my shutter frame and attachment members, all of which will hereinafter be set forth in detail.

Reference is had to the accompanying two sheets of drawings which are illustrative of a specific embodiment of my invention, and in which drawings:

Fig. 1 is a fragmentary perspective view showing the general arrangement of an untrimmed automobile radiator prior to having my V-front shutter applied thereto, while Fig. 2 is a top view thereof inclusive of my shutter devices.

Fig. 3 represents a partial vertical sectional view of said radiator with my shutter assembled thereon, as taken along line 3—3 of Fig. 2.

Fig. 4 illustrates a horizontal sectional view of the aforesaid assembly as taken along line 4—4 of Fig. 3.

Fig. 5 is an elevational front view of my attachable shutter frame ready to be assembled in place on the Fig. 1 type of radiator, a portion of the

frame grille being cut away to more clearly disclose the slats lying therebehind.

Fig. 6 details a clamp bolt as taken along the line 6—6 of Fig. 5, that may be used in fastening my shutter frame to the core shell. 60

Fig. 7 shows a fragmental sectional view of a modified or flat type of shutter frame associated with a regular radiator shell.

Referring first to Fig. 1, this is intended to outline certain of the more conventional motor radiator elements indirectly associated with my shutter devices including the following parts: the vehicle motor 10 mounted to bridge a pair of chassis beams 11; the sectional motor hood 12; a honey-comb or similar type of cellular 70 radiator core 13 of rectangular shape; the upper radiator tank 14 and the lower radiator tank 15 which latter is concealed behind the frame apron 16; and a radiator housing shell 17 adapted to embracingly trim said tanks and the end 75 faces of said core.

In the present instance, the front face 13B of the relatively thin core 13 may be kept flat as represented in Fig. 4 while the front wall of the top tank is flared forwardly and upwardly from 80 the top core edge for the purpose of cooperating with my V-shaped shutter installation. The desired ornamental car appearance is herein attained by the use of simple means designed to reduce the cost of shell fabrication to a minimum. Instead of the conventional stamped-up one-piece radiator shell, I prefer to resort to rolled or otherwise formed up sheet-metal strips having a modified channel shaped or G-like 85 cross-sectional contour providing for a rearwardly extending offset or depressed hood-lip 19 adapted to house the core.

Such strips of uniform width are preferably given a U-shape as indicated in Fig. 1 of which the medial or yoke portion may be additionally 95 bent forwardly into a laterally offset V nose 18 in the flute-like fashion represented in Fig. 2. The inverted U-shaped core shell is disposed to bridge the spaced chassis beams in a straddled relation to the radiator core and the respective 100 depending shell legs running along the core end faces 13A, may be secured in place by the brackets 20. The complementary side-flanges of said channel-like strips such as 17A, are turned inwardly to provide for a smooth exterior web-face for the shell adapted to be highly finished. When such strips are doubly bent as in Fig. 1, it is preferred to build up the housing shell into two separately formed and oppositely disposed 105 pieces which are welded or otherwise fixedly ad- 110

joined at 21. The resulting seam is shown concealed underneath the attachable blinder 22 which may be die-cast into an ornamental configuration and riveted to the shell. The rear 5 end of said blinder is socketed at 23 to mount the pintle of the medial topmost hood hinge. The flared front wall of the tank 14 preferably terminates in an overlapping jointed relation to the inturned forward shell flange 17A in order 10 to reduce air-flow leakage around the upper tank. A tank filler tube may extend through aligned apertures in both the blinder and shell as shown in Fig. 3.

The last named figure also details the disposition of the lower tank 15 which may be provided with a through tube 24 for engine cranking purposes. The separately formed and inset type of radiator apron 16 is mounted ahead of this tank and carries an offset marginal beading 25 designed to cooperate with my shutter frame presently to be described. The plan view of said bead (see Fig. 4) is given a V-shaped contour and the apron extends rearwardly therefrom to provide for an air-flow seal.

25 In order to maintain the desired fixed width for the finished web-wall of the radiator shell, the topmost or yoke forming portion of the hood-lip 19 may be given a reversed V-shape relative to the nose 18 and the forward edge of the sectional hood 12 may be extended to follow up and maintain its overlapping relation with such counterpart lip indentation, as shown in Fig. 2.

Turning now to the structural details embodied in my attachable shutter appurtenances, 35 these essentially comprise a common sheet-metal frame 26 adapted to be mounted wholly ahead of the Fig. 1 assembly as indicated in Figs. 2 and 4. This combined shutter and grille framework may be stamped up integrally but is preferably bent up out of channel-shaped strips in the manner of the radiator shell 17, except that said fenestrated frame is made up into separate pieces respectively adjoined into the endless or 40 annular fashion shown in Fig. 5 and in which the top and bottom bridging elements may each be indented to conform with the juxtaposed V-shape given to the shell nose 18. Said bottom element may be nested and supported in the apron-bead 25 through a suitable cushioning medium 25A. The frame 26 may also be provided with supplementary angle-shaped legs 27 adapted to rest upon the respective chassis beams.

The complementary side-flanges 26A and 26B of said frame strip are also turned inwardly as 55 indicated in Fig. 4 and the smooth web exterior may be nickel finished. The web-wall of the frame 26 is preferably disposed to align endwise with the corresponding wall of the shell 17 to constitute a virtual continuation thereof, 60 the abutting corner regions of the respective profiles being kept relatively sharp in order not to accentuate the location of such joint. The rear flange 26B is spacedly apertured for the 65 reception of the resilient buffer buttons 28 of which the interposed head abuts the radiator shell for cushioning purposes. A plurality of J-bolt fastenings 29 may be used to draw the shutter frame toward said shell, the hook end of each such bolt being interlocked behind the 70 forward shell flange 17A and extending through the front frame flange 26A as shown in Fig. 6. The free threaded shank end of said bolt is preferably made relatively long and an acorn nut 29A tapped throughout its length is applied in place, 75 after which the superfluous shank thread may

be cut off flush with the nut tip to present a neat installation finish.

A perforated sheet-metal screen or grille of the close-mesh wire type 30 is mounted within the shutter frame 26 and may be fixedly secured to the contiguous front flange 26A in the V-like relationship indicated in Fig. 4. Immediately behind said grille, (see Fig. 3) are placed oppositely disposed, top and bottom chord panels 31 and 32 respectively, of which the innermost marginal edges may be beaded and kept parallelly spaced. The outermost edges of these sheet-metal panels may each be given an L-shaped profile to provide for an inturned panel leg such as 31A, that snugly fits between the grille and the rear frame flange.

In the Fig. 5 disclosure, the complementary upright elements of the frame 26 are shown spaced in a substantially parallel relation, the respective outermost shutters being overhangingly disposed behind their contiguous front flanges 26A to adequately control air-flow through the frame opening. Where said frame elements slope toward each other, the respective inset panel ends may be interconnected by stationary dummy slats 100 34A and 34B to square up and provide for a rectangular air-flow opening that can readily be closed by movable slats.

Carried lengthwise behind each innermost edge of the respective chord panels, is a channel-like 105 slat-rack 33 secured to the contiguous panel face. These racks are purposely kept spaced from the inturned frame flange 26A to allow of interposing a grille therebetween. A series of vertically disposed shutter slats 34 are mounted between said 110 racks and these may be pivotally interconnected at their respective uppermost ends to shift in unison. It is preferred to divide the several slats into separate groups by means of sectional tie-rods 35A and 35B as linked at 36 for simultaneous movement. Any suitable means may be employed to actuate the shutters; Fig. 4 shows a cable 37 for this purpose which cooperates with the return spring 38. The respective slat trunnions align with one of the slat edges and are 115 disposed reasonably near the innermost face of the grille. The swinging edge of each slat opens inwardly away from the grille within the frame confines and when closed, the aligned slats snugly approach the adjacent grille without being 120 allowed to strike its innermost face. My parallel slats 34 may be vertically or horizontally disposed and are preferably made relatively narrow to allow of compactly spacing the flanges 125 26A and 26B so as to afford a neat trim for the shell front. Said flange spacing is preferably kept approximately equal to the slat width designated W, in which case the fully opened slats may extend outwardly beyond the rear frame flange.

Fig. 7 shows a flat or non-V-shaped frame 39 as applied to a regular stamped-up radiator shell 40 having a rearwardly faced marginal molding 41 that provides for a clearance chamber 42 between the front core face and the flat rear flange of 130 my modified frame. In such disposition, the respective swinging slat edges may be made to open into said chamber while in the case of the previously described shutter frame 26, its simulated V-front mounting correspondingly provides 135 for an interposed clearance chamber into which to freely swing the opened slats. For such installation, either one or both inturned frame flanges may be bent or otherwise skewed into biplanar relation such that the oppositely dis- 140

posed and forwardly projecting noses 18 are made to lie in substantial registry with the intersecting line of said relatively inclined planes. That is to say, the face of said frame may be laterally offset into a V-shape to provide for a pair of bipartite wings of the kind that are cross-sectionally indicated in Fig. 4. The complementary groups of shutter slats are then respectively arranged in a straddled, lengthwise relation to such intersecting line.

It is emphasized that when the squared-up chord panels and the spanning shutters are given a dark japanned color, they then become substantially concealed behind the grille. In contrast, said grille is preferably given a bright silver-like coating, such that when the installation is viewed in place, the observer's eye becomes focused upon the shiny grille without distinctly seeing or perceiving that a shutter is actually disposed behind such masking grille-work. It will be evident that my shutter frame together with its panels and grille, may be bodily removed at will, although the controlled air-flow opening may readily be made sufficiently liberal that any seasonal removal becomes unnecessary. As a further outstanding feature, my unitary frame 26 cooperates with the radiator shell 17 in serving to cover up the unfinished tank and core fronts that are shown exposed in Fig. 1. The fabrication cost of my simple radiator shell falls far below that of a regular shell of the drawn type, the marked difference usually being such that after making allowance for said trim frame, the total equivalent costs including die charges, may be held down to a minimum without sacrifice in finished car appearance. Where it is desired to prominently display the shutter slats, the grille may be discarded without exposing to view any unfinished radiator parts, the frame 26 then being confined to shutter carrying purposes.

It is thought other advantages inherent in my shutter refinements, will be obvious to those skilled in this art, also that the described improvements are likewise applicable to radiator shutters which are kept flat rather than provided with a simulated V-shaped front, and that various other changes in the structural details may be resorted to in likewise carrying out the illustrative embodiment, all without departing from the spirit and scope of my invention, heretofore described and more particularly pointed out in the appended claims.

I claim:

1. In an automobile shutter assembly serving to control air-flow between a pair of radiator tanks and through an interposed cellular core including a front face and complementary end faces having a U-shaped housing shell mounted astride one of the tanks to shelter the respective core end faces and the cross-section of which shell is given a channel-like profile of which one flange is inturned toward the core, an apron mounted to mask the other tank therebehind and which apron is provided with a marginal bead that extends forwardly of said one inturned flange in a bridging relation to the free flange extremities, and a shutter-carrying frame of the detachable type exteriorly mounted in overlapping relation to the innermost marginal edge of said one flange and which frame is supported upon and extends into cooperative engagement with the apron bead to make an air-seal therewith.

2. In a unitary shutter assembly serving to

control air-flow through a housed cellular radiator core, an endless framework detachably disposed wholly ahead of the radiator housing and pivotally mounting therein a plurality of vertically disposed dull-finished shutters and further comprising a brightly finished grille also mounted within the frame confines and serving to mask the shutters therebehind, the shutter pivots being disposed in close proximity to the grille and about which pivots the respective swinging shutter edges open away from the face of said grille.

3. In a unitary shutter assembly serving to control air-flow through a cellular radiator core comprising a front face and complementary end faces, said core being equiped with a shell housing said end faces and which shell is provided with an inturned forward flange, an annular frame juxtaposed upon the shell flange having a grille mounted within the frame confines to span the annular opening therethrough, spaced complementary panel means also mounted within the frame confines serving to square-up said opening, a plurality of shutter slats carried by the frame and arranged to command the aforesaid squared opening, said panel means and the slats being successively interposed between the grille and the front face of said core, and securing means retaining said interposed members in the recited order within said frame.

4. In a unitary shutter assembly serving to control air-flow through a cellular radiator core having a front face and adjacent opposite end faces that are housed by a shell provided with an inturned forward flange, the combination of an attachable shutter-carrying frame whose cross-section is given a channel-like profile including inturned front and rear flanges, said rear flange being juxtaposed ahead of said forward shell flange, J-bolt means having a relatively long threaded shank end, the opposite end of said bolt being hooked to the forward shell flange with its threaded end projecting through the front frame flange, and a nut of the acorn type applied exteriorly of the last named flange to embrace the threaded shank end therethrough, the axial nut length being kept shorter than the aforesaid projecting threaded shank end and which shank end has the superfluous threads cut off flush with the outermost nut end after bolting up the frame to said shell.

5. In a unitary shutter and grille assembly serving to control air-flow through a cellular radiator core having a front face and which core is housed by a shell, the combination of a single detachable frame mounting a grille and plural shutters in unitary fashion within the frame confines, said frame in its entirety being juxtaposed forwardly of the shell and serving to mask said core face therebehind, cushioning means of the button type interposed between the frame and said shell, and fastening means for attaching said frame to the shell.

6. In a unitary shutter assembly serving to control air-flow through a cellular radiator core that is encased by a shell housing provided with an inturned forward flange, said assembly comprising in combination an endless frame detachably juxtaposed ahead of said shell flange, the cross-section of said frame being given a channel-like profile including inturned front and rear flanges that are spaced apart, a grille disposed interiorly against said front frame flange, panel means mounted between said grille and the rear

- flange and which panel provides for a controllable opening through said frame, a pair of slat racks spacedly carried by said panel, said racks each being provided with a plurality of trunnion-receiving holes that are disposed closely adjacent to said grille, a plurality of shutter slats mounted between said racks and commanding said opening, the opposite ends of each such slat being provided with aligned trunnions respectively 50
- cooperating with certain of said rack holes, and tie-bar means for actuating said slats in unison, the respective swinging edges of said slats being disposed to open away from the face of said grille and to close toward said grille. 10
15. 7. In a unitary shutter assembly serving to control air-flow through a cellular radiator core that is housed by a shell provided with an in-turned forward flange, the combination of an endless sheet-metal frame detachably juxtaposed ahead of said flange, the cross-section of said frame being given a channel-like profile including an inturned front flange and a spaced rear flange that are interconnected by a web-wall and both of which flanges are laterally offset in the direction of said wall to constitute a V-shaped nose for said frame, shutters mounted within said frame and arranged to control the opening therethrough, a grille also mounted in said frame and arranged to mask said shutters therebehind, and air-flow sealing means serving to resist leakage between the housing and said frame. 20
25. 8. In an automobile shutter assembly serving to control air-flow through a cellular radiator core having a front face and which core is housed within a shell provided with an inturned flange arranged to overlappingly cooperate with said core face, the combination of a frame whose cross-sectional profile includes front and rear flanges that are narrowly spaced apart, said rear flange 30
- 40 being juxtaposed wholly ahead of said forward shell flange and providing for a clearance chamber relative to said core face, a grille associated with the front frame flange, and a group of parallelly disposed shutter slats each having aligned end trunnions that are respectively mounted behind said grille in close proximity thereto and each slat having a width crosswise of said trunnions approximately equal to the spacing between said frame flanges, the respective swinging edges of the opened slats extending beyond the rear frame flange into said clearance chamber. 80
9. In a unitary shutter assembly serving to control air-flow through a cellular radiator core that is housed by a shell provided with an in-turned forward flange, the combination of an annular frame detachably juxtaposed ahead of the shell flange and which frame is given a channel-like profile including an inturned front flange and a complementary rear flange, a pair of oppositely disposed slat racks arranged between said rear and front flanges in spaced relationship to the last named flange, a plurality of shutter slats mounted across said racks, and a grille interposed between the front flange and the respective slat racks. 85
10. In an automobile shutter assembly serving to control air-flow through a radiator core that includes a front face, the combination of an annular frame having a cross-sectionally channel shaped profile of which the respective flanges are inturned and a face of which frame is laterally offset into a V-shape to comprise a pair of converging noselike projections respectively disposed in alignment along opposite contour regions of said frame, a grille mounted within the frame confines in a contiguous relation to one of the frame flanges, complementary groups of shutter 90
- 110 slats interposed between said grille and the other frame flange, said slat groups being respectively arranged to each side of the noselike frame projections, and means for detachably mounting said frame wholly ahead of the front core face in 115 a cooperative relation thereto. 165
